BRACELET.

o. 18,739.

Patented Nov. 20, 1888.

UNITED STATES PATENT OFFICE.

SHUBAEL COTTLE, OF NEW YORK, N. Y.

DESIGN FOR A BRACELET.

SPECIFICATION forming part of Design No. 18,739, dated November 20, 1888.

Application filed October 16, 1888. Serial No. 288,282. Term of patent 7 years.

To all whom it may concern:

Be it known that I, SHUBAEL COTTLE, of the city, county, and State of New York, have invented and produced a new and original Design for Bracelets, of which the following is a specification, reference being had to the accompanying photograph, forming part hereof.

My design consists in the configuration of the said bracelet, as hereinafter more particularly specified.

My design presents the appearance of a series of bodies, A, having points B C at their opposite extremities. The sides of said bodies are straight and are at right angles to the plane of the outer faces, and show a regular S-

shaped curvature, the convexity of one side, as at E, being opposite the concavity, as at F, of the other. The said bodies appear in regular succession longitudinally and each overlapping the one next adjacent to it, as shown in the photograph. The outer faces of said bodies appear convex or rounded.

I claim—

The design for a bracelet, substantially as herein shown and described.

SHUBAEL COTTLE.
